UNITED STATES PATENT OFFICE

KINSEL E. MOREE, OF RACINE, WISCONSIN, ASSIGNEE, BY MESNE ASSIGNMENTS, TO
THE MASSEY-HARRIS COMPANY, A CORPORATION OF MARYLAND

TRACTOR

Application filed November 10, 1927. Serial No. 232,288.

The present invention relates to improvements in tractors of the type shown in the patent to Eason and Hendrickson No. 1,205,982, granted November 28, 1916, in which the main frame of the machine comprises a trough-shaped shell in and on which are mounted the engine, transmission, differential, etc., by means of which power is transmitted to the driving wheels, though in some respects, as will hereinafter appear, it is applicable to other types of tractors.

In the construction which form the subject-matter of the present invention, the trough, which is formed of sheet metal, is supplemented and closed at its rear end by a cast metal rear axle housing which is open to the shell. The engine block and the transmission frame casting are mounted on the edges of the trough or shell and are formed with webs cooperating with transverse partitions in the trough to form lubricating chambers for the engine and for the transmission, differential and rear axle driving mechanisms. The invention comprises improved power take-offs, an improved rear axle housing and structure, and other features of invention which will appear from the following description and claims. It is to be understood, however, that the detailed disclosure is for the purpose of exemplification only and that the scope of the invention is defined in the claims in which I have endeavored to distinguish it from the prior art so far as known to me without, however, relinquishing or abandoning any portion or feature thereof.

In the drawings, Fig. 1 is a side elevation of the tractor, partially broken away and in section on a central, vertical, longitudinal plane;

Fig. 2 is a side elevation showing the frame of the tractor with the moving parts omitted;

Fig. 3 is a central, longitudinal, vertical section of the rear portion of the machine on an enlarged scale, parts being shown in elevation;

Fig. 4 is a top plan of the same portion of the tractor with the covering members of the frame removed partly in horizontal section;

Fig. 5 is a horizontal section of a detail but

on a larger scale, parts being shown in elevation;

Fig. 6 is a vertical, central, longitudinal section through a portion of the machine on an enlarged scale, parts being shown in elevation;

Fig. 7 is a transverse vertical section on the broken line 7—7 of Fig. 6;

Fig. 8 is a front view partly in elevation and partly in section of the rear axle housing and its associated parts;

Fig. 9 is an isometric view on an enlarged scale of the transmission mechanism and its mounting;

Fig. 10 is a vertical longitudinal section through a power take-off attachment, parts being shown in elevation;

Fig. 11 is a transverse section through the same on the plane of the broken line 11—11 of Fig. 10, and

Fig. 12 is a side elevation of a detail.

Each part is identified by the same reference character wherever it occurs in the several views.

Referring more particularly to Figs. 1 and 2, the trough-like shell constituting the main longitudinal member of the frame is shown at 20 and the cast metal rear axle housing at 21. A front casting 23 projects into and closes the front end of the shell 20 and is riveted thereto at 24, the front wheels 22 being mounted in the usual manner thereon so that they may be turned for steering the tractor, steering means connected to a steering wheel 25 which may also be of usual construction, being provided.

As heretofore indicated, the shell 20 is bent up from a heavy sheet of metal, preferably steel, of suitable shape to form when so bent a trough having a curved bottom and parallel side walls as best seen in Figs. 2 and 7. The trough is shallower at the front than at the rear end (see Fig. 2) so that when assembled in the tractor, the upper edges are parallel and substantially horizontal, while the bottom inclines downwardly from front to rear. The rear edge of the trough is formed with an outwardly projecting flange 26 by which it is bolted to the cast metal housing 21. Hand holds 27, 27 which may be closed

70

100

by suitable cover plates, are provided at convenient points for access to the interior, and a notch 28 is formed in the edge of the left hand wall for a purpose which will appear. At proper points to divide the oil-containing lubricating chambers from the other portions of the shell, the latter is provided with transverse partitions 29, 30, 31 which may be welded or otherwise secured to the shell to make an oil tight joint. The upper edges of the respective partitions are cut out in V-shape, as shown in Fig. 7 with reference to partition 31, to coact with webs formed on the end crank shaft bearing brackets of the engine block and transmission casting to form sealed, oil proof and dust proof lubricating chambers as will presently appear. Splash pans 33 are mounted at proper positions between the partitions 29 and 30 and on bars 34 to cooperate in the usual way with the connecting rods of the engine to provide splash lubrication. A sump 35 communicating with the interior of the shell through an opening 36 receives oil from the pool 37 in the housing and a pump (not shown) which may be of ordinary lubricating type and connected for driving to the crank shaft, draws oil from the sump and distributes it to the working part of the engine and to the splash pans in a well known and obvious manner.

Except in the respects hereinafter noted, the engine may be of a known or preferred type. The base of the engine block is formed with parallel depending flanges 38 to fit within the upper edges of the trough and outwardly extending flanges 39 designed to rest upon the respective edges of the walls thereof. The engine block casting is secured in position on the walls by bolts extending through the bolt holes 40, 41 in the shell and casting, respectively. The engine block casting also comprises a rearward extension 42 covering the fly wheel 43 and formed with a flange 44 for bolting to a similar flange 45 on the transmission frame casting. It will be noted that the partition 30 is so placed that the fly-wheel is located outside the crank shaft chamber so that the clutch associated with the fly wheel is protected from oil. As usual, the crankshaft is carried in bearings supported in brackets formed with and depending from the engine block casting and the end brackets are formed with webs 46, 47, referred to above, to supplement said partitions 29, 30, respectively, to enclose the crank chamber. As the construction of these webs is similar to that of web 48 on the transmission frame casting cooperating with partition 31, and illustrated in Figs. 3, 6 and 7 it is sufficient to show the latter in detail. Each of these webs is formed on its under V-shaped edge with a channel, such as 49, to receive its respective partition and a packing 50 surrounding the edge of the partition within the channel.

The transmission frame casting, which, as before stated, is bolted to the engine block casting and is likewise supported on the upper edges of the trough or shell, is shown in Figs. 1, 2, 3, 6, 7 and 9. Like the engine casting, it is provided with parallel side flanges 54 to fit within and be bolted to the upper edges of the shell or trough. It is also formed with outwardly extending flanges 55 to rest upon the edges of the trough. This casting supports the stub shaft 60 driven through the clutch by the engine shaft, the transmission and the differential. These several parts and mechanism, except as hereinafter described, are or may be of usual or well known form and are so shown. Specific description is therefore unnecessary. The stub shaft 60 connected to the driven member of the clutch 64 is journaled in a ball bearing 61 supported in a hollow boss 62 formed integral with the web 48 and with the body of the transmission frame casting. The opening of said boss is closed by a cap 63 bolted to the boss and suitably packed to render the joint oil- and dust-proof and through which the stub shaft 60 extends. The clutch is shown, as of usual form, at 64, the clutch shifting sleeve at 65 and the clutch fork at 66. The latter is mounted on a squared shaft 67 journaled in brackets on the transmission frame casting and is accessible through an opening 68 normally covered by cover 69. The shaft is or may be turned through the usual connections and hand lever.

The end of stub shaft 60 remote from the clutch and on the other side of partition 31 and web 48 therefrom, carries a bevel gear 70 which is in mesh with the bevel gear 71, shown in Fig. 3 as partially broken away, the latter being fixed upon the transverse shaft 72, see also Figs. 4 and 5. Shaft 72 is the usual sliding gear shaft of the transmission mechanism. It is journaled at its end in bearings mounted respectively in bosses 73-74 of the transmission frame casting, see Figs. 5 and 9. The bearing in boss 73 comprises a cup 75 containing a conical roller bearing of novel construction. The cylindrical wall of the cup extends beyond the bottom thereof as at 76 and is exteriorly threaded and interiorly grooved at 77, see also Fig. 12. The bottom of the cup is formed at 78 with a kerf or the like for the reception of a tool for turning the cup to adjust the bearing. The wall of the shell is perforated at 79 for the insertion of the turning tool, the opening being normally closed by a plug. A threaded bolt 80 extends through the shell in position to engage one of the grooves of the cup to lock it in adjusted position. The bearing in boss 74 comprises a somewhat similar cup 75' threaded into said boss and containing a similar roller bearing. Shaft 72 extends

through the notch 28, above mentioned, in the shell and receives a power take-off pulley 82 outside such shell. A cover plate 83 with a hole for the shaft is removably bolted over the notch 28 to exclude dust and dirt.

5 The transmission mechanism is, as before stated, of a well-known type and need not therefore be specifically described. It includes the sliding gears 85—86 on the above-mentioned transverse shaft 72, the reversing gear 87 and the duplex or two-diameter gear 88 of the differential with which the first-mentioned gears mesh according to their position, see Fig. 4. The usual gear shifting mechanism is provided for operating the 10 shifting gears. The duplex gear 88 through the usual differential gearing comprising bevel pinions 89 thereon and bevel gears 90, of which one is shown in Fig. 3, drive the countershafts 91, 92. Shafts 91—92 are journaled respectively in brackets 93—94 of the transmission frame casting and carry, respectively, gears 95—96 which are in mesh with master gears 97—98, respectively, mounted on the rear wheel axles.

25 The housing on which the rear wheel axles are journaled and which encloses said master gears, comprises an upper casting 101 and a lower casting 102, said castings being formed at their respective meeting edges with flanges 103, 104 by which they are bolted together. At their front edges these castings are likewise flanged at 105 and 106, respectively, and the flanges are bolted to the flange 26 above mentioned on the rear end of the shell and a flange 107 on the transmission frame casting. Referring, more particularly, to Figs. 2, 3 and 8, it will be seen that the castings 101—102 are formed at their meeting edges with semi-circular recesses 110—111 together forming circular openings which are surrounded by flat seats 112, see particularly Fig. 2. To the respective opposite seats are bolted bosses or sleeves 113—114, through which extend the respective wheel axles 115—116. At the outer end of each sleeve is mounted a roller bearing 117 in which the corresponding wheel axle is journaled. The inner ends of the respective axles are journaled in roller bearing 118 mounted in a bracket 119 formed integral with and rising from the bottom of the lower housing casting. The bracket comprises a strap 120 bolted to the main body thereof, the seat for the bearing above mentioned being formed partially in the main body of the bracket and partially in said strap. The wheel axles are thus provided with widely spaced bearings to firmly support them in proper position. The 30 master gears 97—98 are keyed upon the respective wheel axles adjacent their inner ends.

35 I have provided my improved tractor with a readily detachable power take-off for driving the mechanism of a thresher or other apparatus while the latter is being hauled by the

tractor. With this in view the stub shaft 60, previously mentioned, is provided adjacent the bevel gear 70 with a gear 125, see Figs. 3, 4, and 6. A gear 126 so mounted as to be readily removable from the machine when 40 it is not desired to use the rear power take-off above referred to, meshes with said gear 125, see Figs. 6 and 7. A gear 126 is mounted in a separate frame or support 127 in the nature of a casting extending through an opening 128 formed in the transmission frame casting for the purpose and bolted to the latter at 129. The auxiliary casting 127 comprises brackets 130—141 extending downwardly from the supporting plate of the casting 127 and formed with bosses 132—133, respectively, in which are cylindrical seats 134—135. Roller bearings 136—137 are mounted in the respective seats and carry a sleeve 138. A collar 139 surrounds the sleeve intermediate the bearing and is keyed thereto and also to the gear 126, above mentioned. The sleeve is of somewhat larger diameter at its intermediate collar-receiving portion than toward the end where the inner races of the bearings are seated so that the latter are properly spaced by the enlarged intermediate portions of the sleeve, and the race of bearing 136 is held on the sleeve by a nut 140 threaded on the end of the latter. The outer race of the bearing 137 is adjustable in its seat 135 by means of an annulus 141 bolted to bracket 131 at 142 with an intermediate washer 143 which may be changed to one of another thickness to vary the adjustment of the bearing. The sleeve 126 above mentioned is internally grooved or splined to receive the correspondingly formed end 145 of the power take-off shaft 146 to be now described.

45 Power take-off shaft 146 extends rearwardly through the transmission and rear axle housing and through an opening 148 provided in the rear wall 149 of casting 101 for the purpose, see Figures 3 and 10. A rabbeted seat 150 is machined about the opening 148 and in the outer face of wall 149 to receive a bearing plate 151 which is bolted to the wall of the housing at 152 and is formed with a boss 153 in which the reduced end 154 of shaft 146 is journaled. A collar 155 is clamped upon the shaft 146 and bears against bearing plate 151 to prevent rearward movement of said shaft.

50 The power take-off housing 156 is bolted at 157 to the rear wall of casting 101 about the opening 148 and the bearing plate 151 to enclose and support the parts to be now described. A counter shaft 158 is mounted in alignment with the shaft 146 in bearings 159—160 seated in said housing and extends beyond the housing and is splined at 161. The rear end of the housing is closed by a cover plate 162 having a stuffing box 163 about shaft 158. Rings 164—165 bearing against shoulders formed by an intermediate enlarge-

ment 166 of the shaft prevent longitudinal movement of the latter. A clutch jaw 167 of the helical-tooth type is keyed to the end of shaft 146 and a mating clutch jaw 168 is 5 slidably mounted on the splined end 169 of shaft 158. The rear end of clutch jaw 168 is reduced as at 170 and receives a spring 171 which is compressed between flange 172 of said jaw and a cupped washer 173 on shaft 158. A shifting fork 173 is journaled on a 10 shaft 175, the latter being journaled in lug 176 carried by cover plate 177 and extending into the housing. The fork 174 engages the movable clutch jaw in the usual manner. A 15 handle 178 is mounted on the shaft 175 outside the housing and inside the housing the shaft is provided with an arm 179 having an adjustable stop 180 thereon which engages a pad 181 of the fork.

20 Normally the spring 171 maintains the movable clutch jaw in engagement with the jaw on the shaft 146. But by manipulating the handle in an obvious manner the movable jaw may be withdrawn from engagement.

25 Moreover, the inclination of the jaw teeth is such that in the event that from any cause the shaft 158 moves in the normal direction of drive faster than the shaft 146 or if it moves forward when shaft 146 is stationary, 30 or if shaft 146 is driven backwards or in the reverse direction from the normal, the clutch sleeve 168 backs off thus preventing the shaft 158 from engagement with shaft 146 except when the latter is rotating to drive the former in the proper direction of rotation. Thus, if for any reason during the operation 35 of the tractor and thresher or other machine being hauled and driven by the tractor, the motion of the latter is suddenly checked, 40 the continued motion of the mechanism of the other machine, due to momentum, does not result in strain or injury to any of the parts. The take-off may be readily applied to or removed from the tractor and if desired 45 the tractor may be sold without the attachments, cover plates being provided for the openings, and at a later date the take-off may be procured and applied. In applying the take-off the unit comprising the gear 50 wheel 126 is placed in position, the shaft 145 inserted through the opening 148 and introduced into the sleeve 126^a at its forward end and the bearing plate 151 and the housing 156 bolted in position.

55 Splash lubrication for the gears 125—126 and associated parts is provided by lubricating gear 185.

I claim:

60 1. In a tractor of the class described, a trough-shaped shell, a housing communicating with the rear end of the shell, an engine mounted on the shell near the front end thereof, a transmission mechanism mounted on the shell rearwardly of the engine, wheel axles mounted on and extending into the

housing, master gears on the axles within the housing driven by the transmission mechanism, transverse partitions in the shell forming oil chambers for the engine and transmission mechanism, and webs on the engine 70 and transmission frames in register and cooperating with the partitions in the shell to divide the latter into separate compartments.

2. In a tractor of the class described, a trough-shaped shell, a housing communicating with the rear end of the shell, an engine mounted on the shell near the front end thereof, a transmission mechanism mounted on the shell rearwardly of the engine, axles mounted on and extending into the housing, master gears on the axles within the housing and driven by the transmission mechanism, transverse partitions in the shell and webs on the engine and transmission frames in 75 register and cooperating with the partitions to divide the shell into separate compartments, the lower edges of said webs being grooved and receiving the upper edges of the respective partitions.

3. In a tractor of the class described, a trough-shaped shell, a housing communicating with the rear end of the shell, an engine mounted on the shell near the front end thereof, a transmission mechanism mounted on the shell rearwardly of the engine, axles mounted on and extending into the housing, master gears on the axles within the housing and driven by the transmission mechanism, transverse partitions in the shell the upper edges 90 of which are inclined toward the center, webs on the engine and transmission frames in register with and cooperating with the partitions to divide the shell into separate compartments, the lower edges of said webs being inclined toward the center to match 95 with said partitions.

4. In a tractor of the class described, a trough-shaped shell forming the main portion of the body thereof, means for closing the front end of the shell, the rear wheel axle 110 housing opening into the rear end of the shell, secured thereto and extending above the same, an engine and transmission mechanism mounted upon the upper edges of the shell, the engine and transmission frames being connected together and forming a continuous cover for the shell, the rear end of the transmission frame being connected to the said axle housing, transverse partitions extending across the shell and forming oil 115 compartments for the engine and transmission mechanism, respectively, and webs on the engine and transmission frames in register with said partitions and forming therewith closed compartments in the shell.

5. In a tractor of the class described, a trough-shaped closed shell, means for closing the front end of the shell, a rear axle housing communicating with and closing the rear end 130 of the shell, an engine mounted on the upper

edges of the shell near the front end thereof, the engine frame casting closing the front end of the top opening of the shell, a transmission mechanism likewise mounted on the upper edges of the shell, the frame of said mechanism closing the top opening of the shell between the engine frame casting and said rear axle housing, whereby said trough-shaped shell is substantially closed.

5 10 In testimony whereof, I have subscribed my name.

KINSEL E. MOREE.
